PROCESS FOR REFINING HIGH SULFUR
CRUDE OILSWilliam A. Slater, Hunt, Tex., assignor to Gulf
Oil Corporation, Pittsburgh, Pa., a corporation
of Pennsylvania

Application August 29, 1950, Serial No. 182,096

3 Claims. (Cl. 196—27)

1

This invention relates to an improved process for producing low boiling hydrocarbons from heavy stocks containing residual constituents.

It has been known to up-grade crude oils and other heavy stocks by destructive hydrogenation prior to a cracking treatment. The destructive hydrogenation treatment operates in part to upgrade the heavy portions of the charge, thus producing a cleaner charging stock. The pretreated clean cracking stocks are much more desirable in that they lead to production of substantially lower amounts of heavy bottoms in the cracking reaction. The preliminary hydrogen treatment is of additional advantage in that it effects a substantial lowering of the sulfur content of the virgin stocks. Sulfur is undesirable in the final product, since it leads to corrosion of equipment, corrosion of burners or engines in which it is used, and objectionable odor characteristics.

Prior investigations dealing with the up-grading of residual stocks by destructive hydrogenation, however, have been limited to a species of destructive hydrogenation known as catalytic hydrodesulfurization. An example of up-grading carried out in this manner and then followed by cracking is found in U. S. 1,917,324 to Mathias Pier et al.

The catalytic type of hydrodesulfurization is characterized, among other things, by the use of a relatively sulfur resistant or sulfur immune hydrogenation catalyst such as sulfides of iron, nickel, cobalt, oxides and sulfides of tungsten and molybdenum, molybdates or thiomolybdates and tungstates or thiotungstates of cobalt and nickel. These catalysts cause the sulfur in the charge stock to be converted to hydrogen sulfide. The gaseous hydrogen sulfide is continuously removed from the effluent or conversion product, for example, by absorption into a basic amine solution.

The up-graded cracking stock produced in the first stage of the process described above unfortunately still produces a substantial amount of coke or carbon on the cracking catalyst. Coke laydown, as this phenomenon is termed, deactivates the cracking catalyst and necessitates regeneration thereof. Furthermore, the coke on the catalyst represents a loss in valuable hydrocarbons. Regeneration is normally carried out by burning off the carbon.

Heavy coke laydown is undesirable because it

2

necessitates more frequent and/or more vigorous regeneration of the catalyst which in turn leads to more rapid aging of the catalyst particles. High coke laydown may still further complicate the cracking procedure in that the regeneration system may not have sufficient capacity to remove all the coke formed at a given charge rate. In other words, regenerating systems are limited in the amount of coke which they are capable of burning off in a given time. When the carbon formed on the catalyst exceeds the limit of the regeneration system, the charge rate must be reduced until the coke laydown is reduced to at least the maximum capacity of the regenerator.

10 Reduction of the charge rate is of course reflected in lower output of refined products and is therefore very costly. In addition to the above, regeneration of deactivated catalyst is a necessary and very expensive procedure, particularly with respect to apparatus cost. Therefore, any reduction in regeneration costs, such as produced by decreasing the carbon on the catalyst, is extremely desirable.

One major object of the invention is to provide an improved combination process comprising an up-grading step and a cracking step whereby a hydrocarbon material which contains residual components is converted to gasoline in high yields with low formation of coke. It is a further object to provide a combination process in which the cost of regeneration is reduced. Other objects will appear hereinafter.

These and other objects are accomplished by my invention which comprises a process for treating heavy hydrocarbon oils containing residual constituents. The process includes the step of treating the charge with a material selected from the group consisting of iron, cobalt, nickel, their oxides and combinations thereof. Sulfur in the charge is chemically absorbed on or combined with the metalliferous material described above. The treatment described is carried out at elevated temperature and pressure in the presence of hydrogen. The treatment is terminated before substantial amounts of hydrogen sulfide occur in the effluent. The hydrodesulfurized product is topped to remove at least gasoline, and all or any part of the remaining hydrodesulfurized material heavier than gasoline is cracked to a depth of conversion above about 30 weight per cent. This

is because the gasoline is the product of primary interest. However, in many cases it may also be desirable to remove materials boiling higher than gasoline, such as furnace oil, with the remainder or a suitable cut thereof being sent to the cracking step.

In the following description certain preferred modifications of the invention have been described. It is understood that these are by way of illustration only and are not to be considered as limiting.

Referring briefly to the attached drawings, Figure 1 presents a diagrammatic arrangement of a suitable apparatus for carrying out my two-stage process. Figure 2 is a graphic plot of depth of conversion against coke laydown for a cracking reaction carried out on charge stocks which have been hydrodesulfurized catalytically and by the absorption process.

In the operation of my process I charge a residual-oil-containing charge such as crude to an absorption hydrodesulfurization unit. Absorption hydrodesulfurization may be distinguished from catalytic hydrodesulfurization in that the former employs a catalyst which chemically reacts with or absorbs sulfur contained in the charge, whereas the latter employs a catalyst which is relatively immune to the action of sulfur and which causes conversion of sulfur in the charge to hydrogen sulfide. Also the absorption process is terminated before substantial amounts of hydrogen sulfide occur in the effluent, while the catalytic process inherently necessitates the presence of hydrogen sulfide in the effluent throughout the entire operation.

The charge is treated with a suitable sulfur absorbing contact, e. g., nickel, nickel oxide, or partially reduced nickel oxide, at elevated temperature and pressure in the presence of hydrogen. During the treating process the sulfur in the charge stock reacts with the sulfur absorbent such as nickel or nickel oxide, to form solid nickel sulfide. Hydrogen replaces the sulfur in the hydrocarbon radical thus produced. The sulfur atoms which are replaced by hydrogen may exist in various places in the hydrocarbon molecule. Where the sulfur atom acts as a link between two hydrocarbon radicals, replacement of the sulfur atom with hydrogen may prevent recombination of the molecular fragments, thus producing a desirable shift in API gravity and boiling point. Also a certain amount of ordinary cracking or splitting of high molecular weight molecules occurs, whereby lighter materials are produced. The cracking which takes place may be thermal, catalytic or some of both. However it should be observed that the cracking which occurs in the process does so with a minimum formation of condensed rings and high molecular weight materials (coke or heavy bottoms) which usually accompany ordinary cracking. Another reaction which takes place to a certain extent during the contact period is the saturation of unsaturated linkages in the original or cracked hydrocarbon molecules.

As more charge stock is passed through the catalyst bed, the catalyst particles absorb more and more sulfur. When most of the nickel or nickel oxide has been converted to nickel sulfide, substantial amounts of hydrogen sulfide will begin to appear in the effluent. The processing period is terminated before this point and the charge may be switched to another reactor which is ready to go on-stream. The catalyst in the first reactor is regenerated by passing air

(diluted with steam or inert gas as desired) therethrough. When most of the sulfur and carbon have been burned off, the contacts are ready for reuse in the processing cycle described above.

Following the absorption hydrodesulfurization stage, the hydrodesulfurized crude is topped to remove at least gasoline and lighter constituents, and in some instances the hydrodesulfurized crude may be topped to remove constituents somewhat heavier than gasoline, say the lighter materials down through furnace oil. In either event the remaining material, heavier than gasoline, or a suitable cut of the remainder, is then subjected to a catalytic cracking treatment of known type. The cracking charge is cracked to a depth of conversion above about 30 weight per cent.

The depth of conversion is determined by the conditions under which the process is operated. The conditions necessary to bring about a desired degree of conversion of a given charge stock are obtained by experience. The per cent conversion at given conditions and for a given charge stock may be predetermined by experiment. Since per cent conversion refers to the total gasoline, gas, and coke produced in the process, the determination of conversion depth involves measurement of the amounts of gasoline, gas, and coke formed. In laboratory work, depth of conversion is usually given as weight per cent, while in commercial operations it is usually given as volume per cent. Since the values given in either form are approximately equal, the per cent conversion as used herein and in the claims is meant to include either weight or volume per cent.

Referring now to Figure 1 in detail, in order that my process may be more clearly understood, a fresh charge, for example crude oil, is introduced into the system through line 24. The charge passes from line 24 into heater 26, where it is heated to reaction temperature, or possibly somewhat lower, to allow for the temperature increase across the contact bed. The preheated charge then passes into transfer line 28.

Fresh hydrogen enters the system through lines 2 and 3 and is heated in heater 4 to approximately the same temperature as the charge stock. The preheated hydrogen passes through line 6 to join the preheated charge from line 28. From line 6 the mixture of heated hydrogen and charge stock passes through line 8, through valve 10, through line 12 into reactor 14.

Within the reactor the sulfur in the charge is chemically combined with the metalliferous contact agent. The cracking and hydrogenating reactions described previously also take place.

Converted product passes out of reactor 14 into line 46, through valve 48, into line 50 and into cooler 52, where the products are partially cooled.

When reactor 14 is off-stream reactor 20 is on a processing cycle. In this instance preheated hydrogen and charge stock pass from line 6 through valve 13, into line 16, through line 18 and into reactor 20, where the reactions described above occur. Converted products pass out of reactor 20 through line 54, through valve 56, into line 50 and into cooler 52.

From cooler 52 the partially cooled hydrodesulfurized charge passes through line 70 into separator 72, where an initial separation takes place. Hydrogen dissolved in the product and possibly some gaseous hydrocarbons are flashed off through line 73 into absorber 76. Gaseous

hydrogen and whatever light hydrocarbons are mixed therewith pass out of absorber 76 through line 78 into line 80, from whence they are recycled into the system via line 3 and heater 4. A portion of the gases from line 78 may be bled out through valve 102, line 100, into line 94, through valve 96, into line 98 and vented, in order to prevent the building up of inert materials, e. g., methane, in the recycle hydrogen.

The liquid product in separator 72 passes through line 82 into fractionator 84. Light hydrocarbon gases pass out of the fractionator through line 94 as overhead. From line 94 these gases pass through valve 96 and into line 98 from which they may be vented. The gasoline fraction is removed from fractionator 84 through line 104 into stabilizer 106. C₄ hydrocarbons pass out of the stabilizer as overhead through line 108 and thence to storage. Hydrodesulfurized "straight run" gasoline is removed through line 110 as stabilizer bottoms. The "straight run" gasoline referred to in the accompanying description is the gasoline obtained from the hydrodesulfurized product without further cracking. While it is not purely straight run gasoline in the normal sense in view of the pretreating step, it is essentially straight run in character, being predominantly a saturated type of gasoline line.

Bottoms from fractionator 84 pass through line 86 to charge drum 112 and thence to the second stage of my process. A portion of these bottoms are diverted from line 86 and recycled through line 88, through pump 90, into line 92 and into absorber 76.

When the absorption hydrodesulfurization catalyst contained in reactor 14 has been substantially completely sulfided, substantial amounts of hydrogen sulfide will appear in the effluent. The processing cycle for this reactor is terminated before this time by closing valve 10. By substantial amounts of hydrogen sulfide is meant amounts of this gas sufficient to require removal from the product. For example, gasoline may contain small amounts of hydrogen sulfide without detrimental effects. Large amounts of this impurity, however, render the gasoline unsatisfactory for many purposes and require removal.

It is advantageous to conduct a hydrogen purge of the deactivated catalyst in the off-stream reactor prior to regeneration of the catalyst. This may be accomplished by passing recycle and/or fresh hydrogen through lines 6 and 7 to line 9, through valve 11, through line 15, through line 36, valve 38, line 48, line 12 and into reactor 14. The purge hydrogen at reaction pressure and at about reaction temperature acts to sweep out the converted product remaining in the reactor and also effects a partial conversion of the carbonaceous deposit on the catalyst, thus increasing the total yield and allowing easier regeneration. The purge hydrogen leaves reactor 14 through line 46, through valve 48 into line 50 from which it follows the course of the hydrodesulfurized charge stock. While a hydrogen purge is considered desirable, it is by no means necessary to the invention, since the desirable results of my process are brought about with or without a hydrogen purge.

At the end of the hydrogen purge valve 43 is closed and the reactor is depressured through line 46, valve 60 and line 62.

At the completion of the hydrogen purge a steam purge is considered advantageous in order to remove whatever traces of hydrogen or re-

actants may remain in the reactor. This may be accomplished by passing steam through line 30, heater 32, and into line 34. From line 34 the steam passes through line 36, valve 38 and line 40, through line 12 and into reactor 14. Purge steam leaves the reactor by way of line 46, line 58, valve 60 and into line 62 to vent.

At the completion of the steam purge, air or other oxygen-containing gas (which may be diluted with steam or other inert gas such as flue gas) is passed through line 30, through heater 32 and into line 34. From line 34 the regenerating gas passes through line 36, valve 38, line 40, line 12 and into reactor 14. The regenerating gas operates to burn off the contaminants on the metalliferous contact in the reactor. Flue gas leaves reactor 14 by way of line 46, line 58, valve 60, and line 62. From line 62 the flue gas may be vented. Alternatively, the flue gas may be passed through a scrubber (not shown) to remove sulfur dioxide and recycled as a diluent into the regenerating gas entering the system through line 30.

When reactor 20 is off-stream, purge hydrogen passes from line 6, through line 7, through valve 17, through line 19, valve 42, lines 44 and 18, and into reactor 20. Purge hydrogen and purged product leave reactor 20 through line 54 and valve 56 and pass into line 50, from which these materials follow the course described for the hydrodesulfurized charge stock. Reactor 20 is depressured through line 54, line 55, valve 68 and line 62. Purge steam passes from line 34 through valve 42, through line 44, through line 18 and into reactor 20. Steam and purged products are vented through line 54, line 55, through valve 68, and into line 62. Regenerating gases flow from line 34 into reactor 20 following the same course as that described for the purging steam.

The topped hydrodesulfurized crude passes from charge drum 112 through line 114 into heater 116, where it is heated to cracking temperature. From the heater the preheated cracking stock passes through line 118 into lines 120 and 122 and into the catalyst bed in cracking reactor 126.

Although a Thermofor catalytic cracking unit has been illustrated in the drawing it will be understood, of course, that any other conventional type of catalytic cracking apparatus, employing a fluidized, fixed or moving bed, may be employed.

Active catalyst is continuously supplied to reactor 126 from the top of catalyst elevator 124 by means of catalyst transfer line 128. Deactivated cracking catalyst leaves reactor 126 continuously by way of transfer line 130 and is conveyed from the bottom to the top of catalyst elevator 132. From the top of elevator 132, the deactivated catalyst passes to regenerator 136 by way of line 134. An oxygen-containing gas such as air is continuously introduced into regenerator 136 by means of lines 140 and 142 in order to burn off the coke which has been deposited on the catalyst. Flue gas passes out of regenerator 136 through lines 141 and 143. The exothermic heat of the regenerating reaction is removed by circulating cooling fluid such as water through lines 144 and 146. The water takes up the heat of regeneration and leaves the regenerator as steam through lines 145 and 147. Hot regenerated catalyst leaves regenerator 136 at its lower end and passes through line 138 to the lower end of catalyst elevator 124. The hot

regenerated catalyst is then again passed from the top of catalyst elevator 124 through line 128 and into reactor 126. Hydrating steam may be supplied to the cracking reactor 126 through line 148.

The products of the cracking reaction which takes place in reactor 126 pass through line 149 into fractionator 150. Hydrocarbon gases leave the fractionator as overhead through line 152 and bottoms are removed through line 154. Intermediate fractions, including gasoline, are removed through lines 156, 158 and 160.

It will be understood, of course, that the attached drawing is purely schematic, consequently, all valves, pumps, recycle drums and like details have not been shown. However, the equipment illustrated in the drawing is entirely conventional and omitted details may be readily supplied by one skilled in the art.

As mentioned previously, the utilizing of absorption hydrodesulfurization prior to cracking has among its unique achievements those most important advantages of lower coke laydown on the cracking catalyst and improved gasoline yield. In order to show these and other advantageous results more clearly I have presented below data comparing the results of absorption hydrodesulfurization following by cracking with results obtained by catalytic hydrodesulfurization followed by cracking. Table I presents the laboratory inspections on the charge. The left-hand column gives information on the charge which was hydrodesulfurized by the absorption method in run A. The right-hand column describes the charge used in run B, a catalytic hydrodesulfurization.

Regarding the significance of Tables I, II and III, both runs A and B were carried out on a whole desalts West Texas crude of substantially identical properties and under substantially the same conditions. The absorption hydrodesulfurization (run A) employed a nickel oxide catalyst, while the catalytic hydrodesulfurization (run B) utilized a nickel tungstate, sulfur-immune catalyst. The catalyst in each run was supported on a commercial carrier. It should be noted that the catalyst carbon in the absorption process was 0.95 per cent by weight of charge, whereas in the catalytic process it was 1.67 per cent by weight of charge.

Table IV presents conversion data obtained by cracking the hydrodesulfurized crude obtained from test runs A and B illustrated in Tables I, II and III.

The hydrodesulfurized crudes in each case were topped to remove gasoline and lighter prior to the cracking treatment. Eight runs on the topped crudes were made, three on the topped catalytically hydrodesulfurized crude and five on the absorption hydrodesulfurized crude. The runs were made at comparative space velocities for each charge, with other conditions being substantially identical.

TABLE IV

Conversion index tests on topped hydrodesulfurized West Texas crude

¹ Topped after hydrodesulfurization to remove 400° F. EP gasoline before cracking.

Figure 2 is a semilogarithmic graph plotting the results shown in Table IV and, more specifically, plotting the weight per cent conversion for each type of charge against the weight per cent of coke. It will be seen that above about 30 weight per cent conversion (30 weight per cent gasoline, gas and coke) the carbon laydown is less for the cracking stock which has been hydrodesulfurized by the absorption method (curve A) than for the catalytically hydrodesulfurized cracking stock (curve C). This effect is totally unpredictable as will be seen from reference to Table III. This table shows that the carbon residue on bottoms was 0.88 per cent for the absorption hydrodesulfurized product as compared to 0.35 per cent for catalytically hydrodesulfurized product, or more than twice as great.

In order to bring out the full import of the difference in coke laydown produced by the two types of cracking stocks it should be pointed out that at 40 per cent conversion, for example, the difference in coke deposited is about 0.7 per cent. When charging 20,000 barrels of cracking stock per day (approximately 300 pounds per bbl. or 6,000,000 pounds charged) this difference is equal

reduced hydrodesulfurized West Texas crude obtained by the absorption hydrodesulfurization method. The information under runs 3 and 4 represents the results obtained from fluid catalytic cracking of reduced catalytically hydrodesulfurized West Texas crude. The charge in runs 1 and 2 was obtained by topping the product obtained from run A (Tables II and III) to remove constituents boiling below about 625° F. The charge stock of runs 3 and 4 was obtained by removing the front ends of the product from run B (Tables II and III) to the same point. The cracking charge employed in runs 1-4 therefore was the remaining bottoms boiling above about 625° F.

Table V describes the characteristics of the two pretreated charges. The distillation data in this table indicates that the absorption hydrodesulfurized charge contained the heavier or higher boiling constituents. This is of interest, since despite this fact, the cracking stock from the treated charge produced a higher percentage of gasoline and laid down much less coke. This is additionally unexpected in view of the higher carbon residue on the cracking charge obtained by absorption hydrodesulfurization.

TABLE V

¹ Per Cent @ 392° F. by ASTM D-158-41 Distillation.

In order to illustrate that the advantages of my process are not limited merely to fluidized cracking, data obtained from the fixed-bed cracking of reduced hydrodesulfurized West Texas crude are presented in Table IX. The cracking stock employed in run 5 was identical with that used in runs 1 and 2 (Table V). The cracking stock of run 6 was identical with that employed in runs 3 and 4 (Table V). It will be noted that runs 5 and 6 of Table IX were carried out to approximately identical depths of conversion. The coke on catalyst was substantially lower in run 5 than in run 6, again despite the fact that carbon residue for the cracking charge of run 5 was higher than that for run 6.

The data set forth in Tables I-IX clearly illustrate the unique benefits of absorption hydrodesulfurization in the two-stage process. Coke lay-down on the cracking catalyst is reduced substantially. Furthermore, a greater yield of gasoline is realized. These advantages are accomplished with the concurrent reduction in sulfur contained in the virgin charge.

Since the first stage of my process (absorption hydrodesulfurization) is concerned with treatment of charge stocks containing residual constituents which require extensive conversion, I prefer to employ rather high temperatures desirably between about 750° and 950° F., and particularly in the range of about 800°-870° F., although lower or higher temperatures may be employed. Pressures in the hydrodesulfurization stage may vary between about 100 and 1500 p. s. i. g. Pressures of about 500 to 1000 p. s. i. g. are preferred. Cost of equipment is kept low, and hydrogen consumption is quite low at these relatively low pressures. The hydrogen:oil ratio during the hydrodesulfurization reaction may vary quite widely between about 1000 and about 20,000 cubic feet of hydrogen per barrel of oil and preferably between about 5000 and 12,000 ft.³ H₂/bbl. oil. Space velocities may vary between about 0.2 and about 6 and preferably between about 0.5 and 2.0 liquid volumes of oil per volume of catalyst per hour. Throughput advantageously varies between about 1 and about 10, with a throughput of about 2-8 being very satisfactory in most cases. The space velocity and throughput vary according to the type of charge stock, i. e., its content of heavy constituents, and the degree of desulfurization and conversion desired. I have found that any hydrogen purity above about 50 per cent is satisfactory.

The hydrodesulfurization catalyst employed in my process may be any iron group metal (iron, cobalt and nickel), iron group metal oxides, or combinations of one or more of these metals and/or their oxides, desirably deposited on a porous support or carrier. Nickeliferous catalysts are preferred.

When employed in conjunction with a carrier the contact agents may be made by impregnation of the porous support or carrier with a solution of a soluble salt, such as a nitrate, followed by calcining to form the oxide, and followed by reduction if a metal or a mixture of metal oxides is to be used. Relatively large amounts of metal

or metal oxides should be deposited on the carrier and preferably from about 2 to about 30 per cent. Examples of suitable porous carriers are activated alumina, silica-alumina cracking catalysts of conventional type prepared synthetically or by acid treatment of clays, silica gel, Magnesol, Porocel, Alfrax, kieselguhr and others.

My invention is applicable to hydrocarbon oil charge stocks containing residual constituents. By residual constituents I mean difficulty vaporizable hydrocarbons or hydrocarbons which cannot be vaporized in conventional commercial heaters without substantial decomposition. These heavy constituents form part of the residuum from ordinary distillations, hence the name "residual." Thus the charge stock to the initial or absorption hydrodesulfurization stage may be, for example, crude oil or topped or reduced crude. The hydrodesulfurized product from the first stage is topped to remove at least gasoline and lighter constituents and either the entire remainder, including the hydrodesulfurized residual constituents or a suitable cut therefrom, such as gas oil, may be charged to the second or catalytic cracking stage.

The conditions and catalysts employed in the cracking stage form no part of my invention. Consequently, it is considered unnecessary to list these in detail, particularly since these catalysts and conditions are well known to the art.

One principal advantage of my invention is in the reduced coke laydown on the cracking catalyst. This is accomplished while at the same time increasing the yield of cracked gasoline. The reduction of coke laydown is advantageous in view of the decreased regeneration requirements. Other advantages include production of the following: low sulfur cracked and straight run gasoline products without need of acid treating; high ASTM octane numbers, clear and leaded for straight run gasoline; reduced corrosion and maintenance costs on equipment; reduced sulfur content of cracked fuel gas and fuel oil; low viscosity and low yield of tar; low sulfur content of the C₄ fraction, and reduced regeneration requirements for both the cracking and hydrogenating catalysts.

What I claim is:

1. A process for treating a sulfur-containing hydrocarbon oil selected from the group consisting of crude oil, topped crude, and reduced crude, comprising contacting the oil with a material selected from the group consisting of iron, nickel, cobalt, their oxides and combinations thereof, in a first zone at elevated temperature and pressure and in the presence of added hydrogen, chemically absorbing sulfur in the oil on said material, terminating the contacting before substantial amounts of hydrogen sulfide occur in the product, topping the desulfurized product to remove at least gasoline and lighter constituents, catalytically cracking the remainder in a second zone isolated from the first zone, said second zone being maintained at cracking temperature and containing a cracking catalyst incapable of chemically absorbing substantial amounts of sulfur,

said catalytic cracking being carried out to a depth of conversion of at least about 30 per cent.

2. A process for treating a sulfur-containing hydrocarbon oil selected from the group consisting of crude oil, topped crude and reduced crude, comprising contacting the oil with a material selected from the group consisting of iron, nickel, cobalt, their oxides and combinations thereof, at a temperature between about 750° and about 950° F. at a pressure between about 100 and about 1500 p. s. i. g. in the presence of added hydrogen, said contacting being carried out at a space velocity between about 0.2 and about 6 liquid volumes of oil per volume of catalyst per hour and at a hydrogen : oil ratio of between about 1000 and about 20,000 cubic feet of hydrogen per barrel of oil, chemically absorbing sulfur in the oil on said material, terminating the contacting before substantial amounts of hydrogen sulfide occur in the product, topping the desulfurized product to remove at least gasoline and lighter constituents, catalytically cracking the remainder in a second zone isolated from the first zone, said second zone being maintained at cracking temperature and containing a cracking catalyst incapable of chemically absorbing substantial amounts of sulfur, said catalytic cracking being carried out to a depth of conversion of at least about 30 per cent.

3. A process for treating a sulfur-containing hydrocarbon oil selected from the group consisting of crude oil, topped crude and reduced crude comprising contacting the oil with a material selected from the group consisting of iron, nickel, cobalt, their oxides and combinations thereof, in a first zone at a temperature between about 800° and about 870° F. and at a pressure between about 500 and about 1000 p. s. i. g. in the presence of added hydrogen, said contacting being carried out at a space velocity between about 0.5 and about 2.0 liquid volumes of oil per volume of catalyst per hour and at a hydrogen : oil ratio of between about 5000 and about 12,000 cubic feet of hydrogen per barrel of oil, chemically absorbing sulfur in the oil on said material, terminating the contacting before substantial amounts of hydrogen sulfide occur in the product, topping the desulfurized product to remove at least gasoline and lighter constituents, catalytically cracking the remainder in a second zone isolated from the first zone, said second zone being maintained at cracking temperature and containing a cracking catalyst incapable of chemically absorbing substantial amounts of sulfur, said catalytic cracking being carried out to a depth of conversion of at least about 30 per cent.
